United States Patent Office.

JAMES S. RAY, OF EAST HADDAM, CONNECTICUT.

Design No. 2,826, dated November 5, 1867.

DESIGN FOR A COFFIN-HANDLE.

The Schedule referred to in these Letters Patent and making part of the same.

TO ALL WHOM IT MAY CONCERN:

Be it known that I, JAMES S. RAY, of East Haddam, in the county of Middlesex, and State of Connecticut, have invented a new Design for Coffin-Handles; and I do hereby declare that the following is a full, clear, and exact description of the same, reference being had to the accompanying drawings, making a portion of this specification, in which—

Figure 1 is a plan view of a coffin-handle constructed according to my design.

Figure 2, a transverse section showing more fully the shape or configuration of one portion of the same.

Similar letters of reference indicate corresponding parts in both figures.

A represents the fixed plates by which the handle proper is attached to the coffin. The central portion A of each of these plates, in the inner sides of which the ends of the handle itself are pivoted, is raised up and elevated above the remaining surface of the said plate, as shown more fully in fig. 2, and is made in the shape of a cross, as represented in fig. 1. This cross-shaped portion A* of each plate A is made greatest at its base and extended around the inclined sides thus formed, is a head or milled rib, a. Formed in relief, upon the upper surface of the circumferential portion of each plate, and surrounding the central cross-shaped portion A of the same, is a vine-shaped wreath or figure, b, intended to represent or imitate the trefoil or shamrock. The handle proper is marked B, and is bent in the form shown in fig. 1; and formed upon what, when the handle attached to the coffin, will be the outer side of the said handle are figures, of which those situated, one at each end of the said handle, represent crossed torches c, encircled at their point of intersection by a wreath, d, and having at or near their small ends two crossed branches e, and near their larger or inner ends a transverse braided band, f, wound upon which is a ribbon, g. Situated at the central part of the aforesaid side of the handle B is the figure h of a book, upon which is laid a crook, i, and a mitre, m; and placed one at either side of this last-named figure, and between the same and those just described, as at the end portions of the handle, the curved or drooping figure n of a tree, underneath which, in a sitting and bowed position, is the representation r of an angel. The two opposite edges of the handle B are milled or beaded at different parts thereof, as shown at s.

What I claim as my invention, and desire to secure by Letters Patent, is—

The design and configuration of a coffin-handle herein shown and described.

JAMES S. RAY.
